UNITED STATES PATENT OFFICE.

HORACE HOLMES, OF DETROIT, MICHIGAN.

CARVING-MACHINE.

SPECIFICATION forming part of Letters Patent No. 413,722, dated October 29, 1889.

Application filed June 15, 1889. Serial No. 314,370. (No model.)

To all whom it may concern:

Be it known that I, HORACE HOLMES, a citizen of the United States, residing at Detroit, county of Wayne, State of Michigan, have 5 invented a certain new and useful Improvement in Carving-Machines; and I declare the following to be a full, clear, and exact description of the invention, such as will enable others skilled in the art to which it pertains 10 to make and use the same, reference being had to the accompanying drawings, which form a part of this specification.

In the drawings, Figure 1 is a plan view, and Fig. 2 is a side elevation, of a machine 15 embodying my invention.

It is the purpose of my invention to produce a machine with a rotary cutter, in which the cutter is adapted to be operated at any point on an irregular surface, the construction being such that the tool may be brought 20 opposite the top, bottom, or any side of the object, and may be fed to its work longitudinally of the tool in every possible direction, and may be shifted laterally in any direction 25 from any point without changing the direction of the shaft of the tool itself. The tool is adapted for a variety of work; but is especially valuable as a carving-machine in the production of original work or in the reproduction 30 of work in duplication of a fixed model or pattern.

To this end, A represents a suitable bed or guide plate.

B is a carriage provided with supporting-wheels b, which traverse upon said bed along a suitable guide or way.

C is a shaft journaled in the carriage B. At its ends are fittings C', fixed to the shaft and having upright pivot-journals c'.

40 D represents arms with yokes d at one end, which engage the pivot-journals c'.

F is a shaft journaled in bearings F', and these latter bearings have upright pivot-journals f, which engage yokes d' on the arms D. 45 On the shaft F is fixed a tool-holder G, which also supports an electric motor H, the latter being suitably engaged with the tool G'. In the drawings the tool is in continuation of the armature-shaft of the motor.

50 F² is a spring on the shaft engaged at one end with the shaft and at the other with the

fitting F'. It is designed to balance, as near as may be, the weight of the tool and other apparatus mounted on the shaft.

J is a guide-holder for the guide-point J', 55 designed for use when the machine is employed for making duplicates of a carving.

The tool G' and the guide-point J' are both adjusted upon pivot-shafts g, and upon these shafts are fixed the gears K. K' is a rack-bar 60 engaged with said gears, so that motion given to either gear will be communicated to the other.

L is a weight designed to counterpoise the 65 said apparatus.

The operation of the device will now be understood.

The carving or design to be reproduced, which I term the "model," is placed beneath the guide-point J', while the block to be 70 carved is placed below the tool G'. Both are fixed to a suitable carriage or support, so that any movement of the model with respect to the guide-point will cause an exactly similar movement of the block with respect to 75 the tool. Now, as the arms have a free movement up or down about the axis F and a free movement laterally about the pivot-journals c', and as the tool and point holders G and J have a free movement up and down about 80 the axis of the shaft F, while the guide-point J' and tool G' may move about their pivot-shafts g, it is apparent that said point and tool may be operated in every possible direction, and as the point J' may thus be brought 85 to bear directly upon every part of the model, so the tool will work down to a corresponding point in the block that is being carved.

It is apparent that the tool may be handled directly in making original work, in which 90 case the point J' would not be required, as no model would be employed.

I would have it understood that any convenient means may be employed for holding the block and the model and causing them 95 to feed so that any movement of one will be accompanied by a simultaneous and exactly similar movement of the other. Such mechanism is not shown, as it constitutes no essential part of my present invention.

100 What I claim is—

1. A carving-machine consisting, essentially,

of a carriage, a guide bed or ways along which it is designed to traverse, a horizontal shaft mounted transversely across said carriage, with arms pivotally engaged therewith and 5 adapted to swing horizontally, a horizontal shaft journaled through pivoted bearings at the outer ends of said arms, a tool-support engaged with said latter shaft adapted to move up and down about the axis of the shaft, a 10 tool engaged with a pivot in said support at right angles with the said shaft, and an electric motor engaged with and adapted to rotate the tool, substantially as and for the purposes described.

15 2. The combination, with the tool and the mechanism whereby it is engaged with the

traveling carriage, of the guide-point J', pivoted in like manner as the tool, the gears K, and rack-bars K', whereby the movements of the guide are reproduced by the tool, substantially as described. 20

3. The combination, with the tool, the traveling carriage, and the intermediate connecting apparatus, of a counterpoise - weight L and spring F², substantially as described. 25

In testimony whereof I sign this specification in the presence of two witnesses.

HORACE HOLMES.
